UNITED STATES PATENT OFFICE.

SHERMAN W. CADY, OF HAMILTON, ONTARIO, CANADA, ASSIGNOR TO INTERNATIONAL HARVESTER COMPANY, A CORPORATION OF NEW JERSEY.

BALANCED-AXLE CULTIVATOR.

1,358,057.

Specification of Letters Patent.

Patented Nov. 9, 1920.

Application filed February 24, 1920. Serial No. 360,599.

To all whom it may concern:

- Be it known that I, SHERMAN W. CADY, a citizen of the United States, residing at Hamilton, in the county of Wentworth and the Province of Ontario, Dominion of Canada, have invented certain new and useful Improvements in Balanced-Axle Cultivators, of which the following is a full, clear, and exact specification.
- 10 This invention relates to tillage implements and is shown illustrated in connection with a type of straddle row cultivator shown in a copending application of Charles Sharp #53,945, filed October 4, 1915.
- 15 The general arrangement of the cultivator, to which the invention is shown applied, comprises an arched wheel axle having forwardly extending arms swiveled thereto, the arms carrying the supporting wheels near the swiveled connection with the axle and at their forward ends being connected with a cross member to which the gang frames are attached. In swiveling the wheels by means of foot levers for the purpose of steering the device, the cross member slides laterally with respect to a rigid tongue carrying frame upon which the cross member bears, and in this lateral motion carries with it the gang or tool carrying frames. This results in a multiplied lateral motion of the tool carrying frames with reference to the lateral motion of the cultivator as a whole, as occurs in a number of differently designed cultivators now commonly in use.
- 20 A merit of the above-mentioned type of cultivator is that by rocking the forwardly extending arms, cross connection and wheels as a unit around the vertical portions of the arched axle, the vehicle is steered and the gangs are shifted toward the changed direction of travel without changing their angular setting with respect to the normal line of draft and but a simple mechanism is required.
- 25 The purpose of the present invention is to provide in the type of machine described for properly maintaining its balance as the tool carrying frames are raised and lowered without necessitating material additions thereto or in any way making less satisfactory the normal action of the machine. Such counterbalancing is frequently accomplished by shifting the supporting wheels longitudinally with respect to the tool gang frames, and results in certain disadvantages in construction and action. In the present case counterbalancing is effected by causing the tongue frame, seat and other parts supported thereby to move longitudinally as a unit with respect to the remainder of the machine, in correspondence with the vertical motion of the gang frames. The tendency of the machine to tilt forwardly or rearwardly when the tool carrying frames are raised and lowered is thus counteracted without affecting the action of the mechanism for steering and lateral shifting of the gang.
- 30 Figure 1 is a plan view of the cultivator constructed in accordance with this invention;
- 35 Fig. 2 is a side elevation with one wheel removed and showing the tool frames in lowered position; and
- 40 Fig. 3 is another view like Fig. 2 but with the gang frames in raised position, and with the seat and tongue moved forwardly with respect to the remainder of the machine, as occurs upon the raising of the gang frames.
- 45 Cultivators are usually so arranged that while at work in cutting at some normal or predetermined depth, the reaction of the soil against the soil working tools will be substantially in the line of draft, and therefore such devices have the tendency to rotate around the axis of the supporting wheels only when the tool carrying frames are raised or lowered with respect to their normal working position. This may result in an objectionable vertical motion of the tongue and annoyance to the draft animals, particularly when the tools are raised clear of the ground upon turning at the end of a row. Such action preferably is counteracted in the present design by causing a relative longitudinal motion between main supporting structure of the machine including the supporting wheels and gang frames, and the tongue and seat support, during the raising and lowering of the gangs.
- 50 The cultivator to which the present improvements are applied is shown in the drawings as having supporting wheels 1 journaled on lateral extensions 2 of upwardly and forwardly extending arms 3. These arms are bolted to brackets 4 rotatably mounted on vertically disposed parts 5 of L-shaped axles 6. The upper inwardly extending parts 7 of the axles 6 are, as usual in this type of machine, adjustably secured

within sleeves 8 by means of collars 9, which are partly encircled by end portions of the sleeve.

The axles 6 are in this manner tied together, while the sleeve 8 is free to rotate a limited extent around the portions 7 of the axles. The arms 3 are tied together at their forward ends by a tool beam supporting bar 10 and a transverse I-beam 11. Each arm 3 has a vertical end portion 12 extending into the socket of a bracket member 13, connecting the bar 10 and beam 11. The tool frames 14 carry sleeves 15 at their forward upper ends, encircling the bars 10, and are by means of links 16 and lever 17 secured to the bar to move therewith during the swiveling motion of arms 3 and brackets 4 on the portions of 5 of axles 6. The arms 3, being parallel and moving in an arc around the parts 5, maintain the beam supporting bar 10 parallel with sleeves 8 during the swiveling motion, and accordingly the tool frames 14 are maintained parallel with the normal line of draft when the vehicle 25 is steered to right and left far enough to cause the soil working tools to avoid cutting irregular plants of a row.

The means for effecting the steering action consists of foot levers 18 pivoted to seat frame 19 at 20, and at their forward upper ends being attached to chains 21 which pass around fixed pulleys 22 and then extend inwardly where they are attached to a casting 23 secured to the tool beam supporting bar 10. By this means, when the lower end of one of the foot levers 18 is pushed forwardly, the member 10 is shifted either to the right or to the left, depending which foot lever is forced forwardly, thus swinging the arms 3, brackets 4 and wheels 1 around their pivotal support 5.

In order to adjust the gang frames 14 toward or away from each other so as to operate closer or farther away from a row 45 of plants between the gangs, the lever 17, to which the links 16 are attached at opposite ends may be rotated around its central pivot on casting 23. Rotation of lever 17 is effected by an adjustable and lockable 50 handle 24.

A tongue 25 from which depends the usual swingletrees and hangers 50, is pivoted by bolt 26 to a draft frame 27, forming an extension of seat frame 19, and is vertically 55 adjustable, for the usual purpose of tool frame leveling at different cutting depths, around the bolt 26 by means of a lever 28 which is pivoted to a bracket 29 secured to the rear end of tongue 25 and having a 60 quadrant 30, to which the lever 28 may be locked in its different adjusted positions. The lever 28 is connected by a link 31 to a tie bar 32 of frame 27.

The structure so far mentioned in the reference numbered part of the description is

substantially the same as that shown in the before-mentioned copending application. The present improvements relate particularly to the unit formed by seat support 19 frame 27, tongue 25, and the tool frame raising mechanism which is arranged to impart longitudinal motion to said unit during the raising and lowering of the tool frames.

The following description relates to the construction and operation of the new features:

The seat support 19 and the draft frame 27 are secured together by yoke-shaped castings 33 and connecting links 34 which are respectively riveted to the frames 19 and 27 by the rivets 35, and 36 and 20. The castings 33 are properly formed to provide bearings for the pulleys 22 and form abutments for the I-beams which normally ride on rollers 37 journaled in the members 33. The gangs are raised and the unit formed by seat frame 19, frame 27 and tongue 25 is shifted forwardly at the same time by means of a lever 38 pivoted to a quadrant 39, in turn attached to frame 27. Forward of its pivot 40 the lever 38 is pivotally connected with a link 41 which extends rearwardly and at its rear end is pivotally connected with an arm 42 rigid with sleeve 8. The frame 27 at its rear end is also pivoted to arms 43 rigid with sleeve 8. Accordingly, when lever 38 is rocked upwardly from a position in which it is shown in Fig. 2 to that shown in Fig. 3, the sleeve 8 is rotated to the right, causing forward movement of the frame 27, seat support 19 and tongue 25 attached thereto with respect to the remainder of the machine. Link 41 serves as a downwardly moving fulcrum for lever 38 so that a horizontal motion only will be imparted to the seat support and tongue.

The sleeve 8 carries quadrants 44 which are normally engaged by locking dogs 45 on individual gang adjusting bell crank 110 levers 46. These levers are accordingly caused to rock to the right upon the right-hand rotation of sleeve 8, as above described. The lower ends of levers 46 are connected by lifting rods 47 with the gang frames 14.

With the construction described, the unit formed by seat support 19, frame 27 and tongue 25 is shiftable forwardly and rearwardly by means of lever 38 which simultaneously acts as a gang raising and lowering lever. The weight of the operator and the tongue is thus shifted forwardly or rearwardly with respect to the pivotal axis 2 according to the extent the shovel gangs are raised or the depths to which the tools thereon are caused to penetrate the soil.

Lifting of the gang frames and forward motion of the seat and tongue unit is assisted by a counterbalancing spring 48 ex-

tending between an arm 49 on sleeve 8 and the yoke-shaped bracket member 33.

While there is shown and described but one embodiment of this invention, it is to be understood that it is capable of many modifications. Changes, therefore, in the construction and arrangement of parts may be made which do not depart from the spirit and scope of the invention, as claimed.

10. I claim—

1. A tillage implement comprising a frame structure including an arched axle and supporting wheels for said frame, a tool carrier mounted on said frame for vertical adjustment, a sleeve on said arched axle and rotatably adjustable thereon, a draft element longitudinally slideable on said frame and connected with said sleeve, whereby rotation of the sleeve affects the longitudinal motion of the draft element, and means for rotating said sleeve and vertically adjusting the tool carrier.

2. A tillage implement comprising a frame structure including an arched axle and supporting wheels for said frame, a tool carrier mounted on said frame for vertical adjustment, a sleeve on said arched axle and rotatably adjustable thereon, a seat longitudinally slideable on said frame and connected with said sleeve whereby rotation of the sleeve affects the longitudinal motion of the seat, and means for rotating said sleeve and vertically adjusting the tool carrier.

3. A tillage implement comprising a frame structure, including an arched axle, longitudinally extending arms swiveled on the vertical portion of the axle, said arms being connected for unitary motion, supporting wheels for said frame shiftable around a vertical axis with said arms, a draft frame supported for longitudinally relative motion by said arched axle, and means for longitudinally adjusting said draft frame with respect to said frame structure.

4. A tillage implement comprising a frame structure, including an arched axle and connected longitudinally extending arms swiveled on vertical portions of said arched axle, supporting wheels journaled at the lower ends of said arched axle and angularly adjustable with said arms with respect to the vertical portions of the arched axle, tool carriers supported for vertical adjustment on said frame, a tongue carried by and longitudinally movable with respect to said frame, and means for vertically adjusting the tool carrier and imparting a

corresponding longitudinal motion to the tongue.

5. A tillage implement comprising a frame structure, including an arched axle and connecting longitudinally extending arms swiveled on vertical portions of said arched axle, supporting wheels journaled at the lower ends of said arched axle and angularly adjustable with said arms with respect to the vertical portions of the arched axle, tool carriers supported for vertical adjustment on said frame, a seat carried by and longitudinally movable with respect to said frame, and means for vertically adjusting the tool carrier and imparting a corresponding longitudinal motion to the seat.

6. A tillage implement comprising a frame structure, including an arched axle and forwardly extending arms, a connection between the forward ends of said arms, a tongue bearing on said connection and movable longitudinally thereof, the tongue being supported at another point by said arched axle through a connection permitting the relative longitudinal motion, and means for securing said tongue at different positions along said frame.

7. A tillage implement comprising a frame structure, including an arched axle and forwardly extending arms, a connection between the forward ends of said arms, a tongue carrying a seat bearing on said connection and movable longitudinally thereof, the tongue being supported at another point by said arched axle through a connection permitting the relative longitudinal motion, and means for securing said tongue at different positions along said frame.

8. A tillage implement comprising a supporting frame structure, said frame structure including forwardly extending arms having a swiveled connection with the remainder of the frame and being connected at their forward ends by a cross member, a tongue bearing on said cross member and longitudinally adjustable with respect to said frame, said tongue and cross member being arranged to permit lateral motion of the cross member with respect to the tongue, and a tool carrying frame supported by said cross member.

In testimony whereof I affix my signature.

SHERMAN W. CADY.
